Primary Examiner — Elizabeth A. Albert(74) *Attorney, Agent, or Firm* — Ulmer & Berne LLP(57) **CLAIM**

The ornamental design for a hydroponic system, as shown and described.

DESCRIPTION

FIG. 1 is a top isometric view of a hydroponic system illustrating the new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top planar view thereof;

FIG. 7 is a bottom planar view thereof; and,

FIG. 8 is a bottom isometric view thereof.

The broken lines in the drawings are included for the purpose of illustrating portions of the hydroponic system that form no part of the claimed design.

1 Claim, 8 Drawing Sheets---
